UNITED STATES PATENT OFFICE.

EDWARD GERMAIN, OF SAGINAW, MICHIGAN.

DESIGN FOR A MANTEL.

SPECIFICATION forming part of Design No. 21,160, dated November 10, 1891.

Application filed October 14, 1891. Serial No. 408,728. Term of patent 7 years.

To all whom it may concern:

Be it known that I, EDWARD GERMAIN, of Saginaw, in the State of Michigan, have invented and produced a new and original Design for Mantels, of which the following is a specification, reference being had to the accompanying drawings, in which—

Figure 1 is a front elevation of the mantel. Fig. 2 is a transverse vertical sectional elevation of the same, intended to more clearly illustrate the outline and configuration of the parts.

In the drawings, *a* are the pilasters; *b*, the plinths; *c*, the brackets; *d*, the mantel-board; *e*, the frieze; *f*, the grounds; *g*, the fire-strips; *h*, the shelf-board. Each pilaster has beveled edges *a'* and a sunken panel *i*, in which is intagliated the representation *i* of a spray or branch of a flowering plant.

The upper portion of the front of each plinth *b* is molded and ornamented, as seen in the drawings, *b'* being the molding and *b''* being pits or sunken dots in the same. Each plinth is surmounted by a pair of brackets *e*. (Shown in face view in Fig. 1 and in side view in Fig. 2.) The shape or configuration and ornamentation of these brackets can best be appreciated by reference to the drawings. They are chamfered on the sides, as at *j*, and bear

at the top and bottom intagliated ornamentation *k*. At the top each pair has a molding *m*, forming a cap for the pair and of the same pattern with the molding *m* immediately beneath the mantel-board.

The frieze *e* has two sunken panels *n*, in each of which is the intagliated representation of a spray of some flowering plant similar to that contained in the panels of the pilasters.

The shelf-board *h* extends along the bottom edge of the frieze and between the two brackets *e* of each pair. It is a narrow horizontal shelf having a molded edge of wavy or undulatory outline, as shown.

The edges of the mantel-board, the fire-strip *g*, and the outer side-strips of the grounds *f* are molded, as shown.

What I claim, and desire to secure by Letters Patent, is—

The design for a mantel, as herein described and shown.

In testimony whereof I affix my signature in presence of two witnesses.

EDWARD GERMAIN.
